ATHLETE'S PROTECTIVE GARMET

Filed Jan. 17, 1923

2 Sheets-Sheet 2

UNITED STATES PATENT OFFICE.

DAVID LEVINSON, OF CHICAGO, ILLINOIS, ASSIGNOR TO WILSON-WESTERN SPORTING GOODS CO., OF CHICAGO, ILLINOIS, A CORPORATION OF DELAWARE.

ATHLETE'S PROTECTIVE GARMENT.

Application filed January 17, 1923. Serial No. 613,103.

The invention relates to athletes' protective garments, and particularly to garments which are primarily designed to be used by baseball players, football players, and other 5 athletes, who, during the playing of a game, slide upon the surface of the field or floor, and in so doing subject their hips, legs, and other parts of their bodies to the possibility of injury.

10 The garment referred to embodies the various features shown, described, and claimed in my copending application for United States Letters Patent, Serial Number 596,260, filed October 23, 1922. It also embodies a number of additional improvements 15 which form the subject matter of this application.

An object of the invention is to provide a garment which will protect the hips, thighs, 20 rear portion, and legs of the player against injury, and to employ pads which are connected together so as to allow relative movement between the pad elements forming the protective parts of the garment.

25 Another object of the invention is to arrange the pads of the garment in sets, which hang at the sides and the rear of the wearer, so that one pad of a set is permitted to slide relatively to another, or to the others of the 30 set, and to connect them together in a way that their proper relative relation will be maintained when they are brought into action and use during sliding and also after sliding.

35 A further object of the invention is to so construct the garment that the number of protective elements or pads may be increased or diminished, according to the wishes of the user.

40 It is a further object of the invention to so construct the garment that certain of the protective elements or pads are readily adjustable, and that they may be shifted and changed in their positions, i. e., they may be 45 raised or lowered to suit the desires of the wearer.

An additional object of the invention is to construct a garment with belt and skirt portions to which the side pads are attached, 50 and to which the rear pads may be attached.

By this construction the strains on the garment arising from use by the player are dis-

tributed and the lasting and wearing qualities of the garment are increased.

One of the specific objects of the invention 55 is to provide the rear portion of the garment with a sliding pad which may be adjustably secured to the rear skirt portion of the garment by means of a cord and eyelet arrangement.

60 A further object of the invention is to construct the rear pad in such a manner that it will effectively and efficiently protect the wearer in the region of the lower termination of the spinal column.

65 The invention will be explained and more readily understood when read in connection with the accompanying drawings, in which one embodiment of the invention is illustrated, it being obvious that changes and modifications may be made without departing from the spirit of the appended claims.

In the drawings:

70 Figure 1 is a rear elevation of an athlete's protective garment constructed according to the invention and showing the rear pad in position on the garment.

75 Figure 2 is a rear elevational view of the garment with the side pads broken away and the rear pad removed.

80 Figure 3 is a section taken on line 3—3 of Figure 1.

Figure 4 is a section taken on line 4—4 of Figure 1.

85 Figure 5 is a section taken on line 5—5 of Figure 1.

90 Figure 6 is an elevational view of a portion of the garment with a part broken away to more clearly show another part of the garment.

95 Figure 7 is a section taken on line 7—7 of Figure 6.

In the design of the particular garment shown in the drawings an adjustable main body portion, generally designated 10, is 95 shown. The body portion has a belt 11, the top edge portion of which is provided with the binding strip 12. The body portion is also provided with a front or abdomen skirt portion 13, and a rear skirt portion 14, 100 which skirt portions are stitched together at the sides and extend downwardly from the belt.

The front or abdomen portion of the gar-

ment has a placket with lacing 15, so that the garment may be adjusted to comfortably fit the wearer.

The belt 11 has at the rear thereof a gore 5 or gusset 16, made of elastic, or other suitable material, to compensate for the expansion and contraction to which the belt is subjected, and to assist in making the garment fit snugly and comfortably.

10 The belt of the garment is reinforced with strips of webbing 17 and 18, which each extend on their respective sides substantially from the placket and lacing 15 to adjacent the elastic gore or gusset 16. A support 19 15 is removably attached to the lower ends of the front and rear skirt portions 13 and 14.

Three sets of sliding pads are provided, two side sets and one rear set. Each set comprises a plurality of pads. Each of the 20 pads designated 20, 21, and 22 is arranged next the body of the wearer. Each of the inner side pads 20 and 21 has its upper, straight end sewed, or otherwise secured, on the inner face of the main body portion 10 25 of the garment. The pads are sewed, or otherwise secured, to the belt 11 at the top, as indicated at 23 and also at 24 in Figure 6. The straight, upper edges of each of the inner side pads 20 and 21 are caught under 30 and secured by the binding strip 12. The inner pads 20 and 21 extend downwardly from the belt portion a suitable distance towards the knees of the wearer and are made with rounded ends. The inner pads are 35 constructed in a manner to protect the wearer under hard and strenuous usage, but, nevertheless in such a way that the wearer may have complete comfort and freedom of movement at all times and in all positions.

40 The inner pads 20 and 21 are each provided with a plurality of eyelets which are in a plurality of rows 25 and 26 arranged transversely of the length of the pad intermediate the ends thereof.

45 One, or more additional pads 27 and 28, which are removable, may be laced by the laces 29, or otherwise secured, in a row of the eyelets. It will be obvious that in case a large amount of padding is desired, one, or 50 more, additional pads 27 and 28 may be laced, or otherwise secured in the other, or others, (if they are provided) of said rows of eyelets in said inner pads. The primary purpose in having the plurality of rows of eyelets in the inner pads 20 and 21 is to permit the removable pads 27 and 28 to be adjustably secured in place. One time the player might like to have the removable pads 27 and 28 hang relatively far down 55 and would use the lowest row of eyelets. At another time he might like to have the pads 27 and 28 raised as far as possible and would use the highest row of eyelets.

Outer pads 31 and 32 are, respectively, 60 associated with the inner pads 20 and 21.

The outer pads are elliptical in shape. The lower portion of each of the outer pads substantially corresponds in outline to the lower portion of the inner pads. The outer pads are connected adjacent their upper edges, as indicated at 33, 34 to the hip portion of the main body 10 of the garment. The outer pads are placed over the inner pads and both hang over and protect the sides, hips, and thighs of the wearer.

75 It will be apparent that, since the inner pads 20 and 21 are secured in straight lines, as shown, to the inner face of the belt and skirt portions of the garment and that the upper, rounded ends of the outer pads 31 and 32 are secured to the outside of the skirt portions of the garment, that the strains ensuing from the relative movement of the pads on each other when the player slides on the ground or floor will be distributed in such a way that the garment will have increased strength and durability.

80 The pairs of pads 20, 21, and 31, 32 are, respectively, connected together at their opposite edges by means of the front and rear connecting bands 35 and 36. These bands may be of elastic or non-elastic material and are constructed to hold and maintain the pairs of inner and outer pads, as well as the intermediate pads, between them and in 85 their proper relation, and to permit them to move relatively to and slide upon each other when they are in use and when the player runs and slides to the desired position. The intermediate, removable pads 90 which are held between the inner and outer pads, hang freely from the line, or lines, of lacing in the row, or rows, of eyelets, 25 and 26, and although between the connecting bands 35 and 36 are not directly connected 95 to them.

100 The intermediate removable, auxiliary pads 27 and 28 are arranged and employed between the pairs of inner and outer pads. Each of the auxiliary or intermediate pads 105 substantially corresponds in design to the inner pads and has a straight, upper portion and a rounded, lower portion. The auxiliary and intermediate pads are provided with eyelets 37. The eyelets in the 110 intermediate pads 27 and 28 are arranged in alignment with the eyelets in the inner pads 20 and 21, so that the attaching cord or lacing 29 may be readily passed through the eyelets of both pads and thereby secure 115 these pads together.

120 The upper edge of each intermediate pad has a reinforcing strip 38 which extends across the entire width of the upper end of the pad and has the eyelets 37 therein.

125 It will be understood that if the player should desire to increase the number of the intermediate pads in either set of side pads, this can readily be done. To accomplish this, it is only necessary to remove the cord, 130

arrange the desired number of intermediate pads, so that the eyelets therein are in alignment with the eyelets in the pads 20 and 21 and then thread the cord or lacing 29 through 5 the eyelets.

The rear set of pads is placed between the side sets and is removably secured to the rear skirt portion 14. The rear skirt portion 14 is provided with a plurality of rows of eyelets 39, 40 and 41. The rows of eyelets are spaced apart below the strips of webbing 17 and 18 and the individual eyelets are arranged on opposite sides of the gusset or gore 16 in vertical alignment with each other. 10 The inner pad 22 of the rear set of pads is designed so that it may be worn with comfort to the player. This pad 22 is provided with a plurality of reinforced eyelets 42 which are arranged adjacent the upper edge 15 of the pad. The eyelets 42 are formed in the material 43 providing a reinforcing band for the upper part of the pad. When it is desired to secure the rear pad 22 to the remainder of the garment the eyelets 42 are 20 brought into alignment with one of the rows of eyelets 39, 40, or 41 provided in the rear skirt portion 14 and the pad is secured to the rear skirt portion by means of the lacing 44 which is threaded through the respective eyeletted openings in the skirt and pad portions and tied so as to secure these elements together. 25

Another pad 45 which is substantially similar in form of outline to the inner rear pad 22 is stitched and secured to the inner pad 22 along the upper edge at 46 and is also stitched and secured to the inner pad along the lower and side edges at 47, 48, and 49 in a manner to permit of relative movement 30 of the pads 22 and 45 with respect to each other.

This last mentioned pad 45 has secured to it a suitably shaped pad 50 of soft material, such as felt, which is arranged between the 35 pad 45 and the inner pad 22. This felt pad 50 is stitched or otherwise secured to the pad 45 to form a pocket in which is enclosed a suitably shaped disc or plate 51 of fibre or other similar and relatively stiff and hard 40 material. The disc or plate 51 is primarily employed to protect the lower end of the spinal column of the wearer. The felt pad 50 provides a cushion for the end of the spine and is placed between the body of the 45 wearer and the fibre disc or plate 51 to provide a cushion between the player and the plate.

It is manifest that by the provision of the eyelets in the skirt portion 14 the pads 50, 22, 45 and 50 and the plate 51 may be moved relatively to the garment to position the plate 51 and the cushion 50 to the desired region of the player's anatomy to be protected.

The inner pads 20 and 21 are provided 60 with the elastic bands 52 and 53. The bands

are connected to the opposite edges of the respective inner pads and with the pads, are designed to encircle the legs of the wearer and hold the pads 20 and 21 in their proper positions with relation to the legs and hips 70 of the wearer.

As before stated, the main body portion 10 is designed with skirt portions which have the support 19 secured thereto. A plurality of buttonholes 54 is placed in the front and 75 rear skirt portions. Buttons 55 are secured to the support 19, whereby the support is buttoned to the skirt portions 13 and 14. This support, it will be readily understood, not only serves to support organs of the 80 player, but holds and maintains the front and rear skirt portions snugly against the body of the wearer and also holds and maintains the three sets of pads firmly on the body of the wearer. 85

From the foregoing it will be understood that an athletic garment is produced which will diminish the friction between the body of the player and the ground or floor, and thus fully protect the player against injury. 90 It will also be understood that the inner and outer pads of each set of pads are secured together, yet permitted and adapted to move and slide with relation to each other.

It is also evident that an athletic garment 95 is produced in which there is cooperation between the three sets of pads in protecting the body of the wearer when he slides, falls or rolls on the ground or floor, and if he collides with or brushes against his opponents. 100

Having thus described the invention, what I claim and desire to secure by Letters Patent is:

1. In a garment of the character described the combination of a belt portion, a pair of 105 members carried by the belt portion and extending downwardly from the rear thereof when worn by a person, said pair of members having a row of eyelets, and said belt portion having a plurality of rows of eyelets, a lacing threaded in said eyelets to adjustably secure said pair of members to said belt portion, said members being connected together for relative movement of portions of said members with respect to each other, 110 a cushioned plate supported and interposed between said members, and said cushioned plate being arranged with respect to said members to locate said cushioned plate adjacent the termination of the spine of the 115 wearer.

2. In a garment of the character described the combination of a belt portion, a detachable pad extending downwardly from the rear only of the belt portion when worn by 120 a person, a cushion and a plate carried by said downwardly extending pad, said cushion and plate being arranged with respect to said pad to locate said cushion and plate adjacent the termination of the spine of the 125 wearer.

130

wearer, and means whereby said cushion and plate may be adjustably held with relation to said belt portion, said means comprising a plurality of rows of eyelets in said belt portion and eyelets in said downwardly extending pad, and a lace threaded in the eyelets of said belt portion and said pad.

3. In a garment of the character described the combination of a belt portion, a pair of members carried by and extending downwardly from the rear of the belt portion when worn by a person, a plate, a cushion, 30 said plate being interposed between the cushion and one of said members, said cushion being secured to said member, said plate and cushion being arranged between said members which extend from the belt portion, said pair of members being secured for movement with respect to portions of each other and adjustably held with relation to said belt portion, and said plate and cushion being located relatively to the member to which they are secured to locate said plate and cushion adjacent the termination 40 of the spine of the wearer.

10 15 20 25

4. In a garment of the character described

the combination of a belt portion, a pair of members carried by and extending downwardly from the rear of the belt portion when worn by a person, a plate, a cushion, 30 said plate being interposed between the cushion and one of said members, said cushion being secured to said member, said plate and cushion being arranged between said members which extend from the belt portion, said pair of members being secured for movement with respect to portions of each other and adjustably held with relation to said belt portion, and said plate and cushion being located relatively to the member to which they are secured to locate said plate and cushion adjacent the termination of the spine of the wearer, said adjustment being secured by means of eyelets, and a lacing in said belt portion and said downwardly extending member to which the cushion is not secured.

45

In witness whereof, I hereunto subscribe my name this 11 day of January, A. D., 1923.

DAVID LEVINSON.
